US00D952858S

(12) **United States Design Patent** (10) **Patent No.:** **US D952,858 S**
Thieme (45) **Date of Patent:** **** May 24, 2022**

(54) **FRONT FACE OF MEDICAL DEVICE**

(71) Applicant: **WEINMANN EMERGENCY MEDICAL TECHNOLOGY GMBH & CO. KG**, Hamburg (DE)

(72) Inventor: **Christian Thieme**, Hamburg (DE)

(73) Assignee: **WEINMANN EMERGENCY MEDICAL TECHNOLOGY GMBH & CO. KG**, Hamburg (DE)

(**) Term: **15 Years**

(21) Appl. No.: **29/727,205**

(22) Filed: **Mar. 9, 2020**

(30) **Foreign Application Priority Data**

Sep. 10, 2019 (DE) 40 2019 100 975.2

(51) **LOC (13) Cl.** **24-01**

(52) **U.S. Cl.**

USPC **D24/167**

(58) **Field of Classification Search**

USPC D24/107, 164–169, 186, 185, 200; D10/70, 98; D14/485–489, 257; D13/162, 164

CPC A61N 1/39; A61N 1/3925; A61N 1/3968; A61N 1/3987; A61N 1/3993

See application file for complete search history.
